UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT.

LOCK.

Application filed April 25, 1924. Serial No. 708,918.

This invention relates to locks, and more particularly to locks adapted for use on the doors of hotel corridors or the like. It is usual to provide locks in such locations so arranged that when the door has been locked from the inside it is not possible to throw the bolt from the outside by the usual key or the maid's key, but only by some key of higher order, such as a master or emergency key. In many instances it happens that when the maid seeks to gain admission to a room so locked with the usual key the key is prevented from turning by wards or mechanism of the lock, and when considerable pressure is applied to it, as is often done, the key becomes mutilated or twisted, and is even at times broken off in the lock, thereby causing considerable trouble and inconvenience.

One object of the present invention, therefore, is the provision of a lock so arranged that when the door is locked from the inside and it is attempted to unlock it from the outside some of the keys at least will rotate idly in the lock and will not be resisted by the lock mechanism, so that there will be no tendency to deform or break the keys.

A further object of the invention is the provision of a novel form of mechanism whereby when the bolt is dead-locked the bolt operating mechanism will be moved out of the path of a roll-back operated by some of the keys so that the roll-back may turn idly without resistance.

A further object of the invention is the provision of a novel form of locking mechanism wherein the roll-back, operated by at least some of the keys from the exterior of the door, will turn idly without contacting with any part of the locking mechanism when the door is dead-locked.

To these and other ends the invention consists in the novel features and combinations of parts to be hereinafter described and claimed.

In the accompanying drawings:—

Fig. 1 is a fragmentary front elevational view of a door and door frame upon which is mounted an indicator lock embodying my improvements;

Fig. 2 is an edge view of a door having mounted thereon a lock embodying my invention;

Fig. 3 is a side view of the lock case with

the cover plate removed to show the lock mechanism;

Fig. 4 is a view similar to Fig. 3, but showing the dead locking mechanism in operative position; 60

Fig. 5 is a sectional view through the indicating mechanism on line 5—5 of Fig. 3;

Fig. 6 is a view similar to Fig. 5 showing the parts in the position in which the indicator button is depressed; 65

Fig. 7 is a sectional view on line 7—7 of Fig. 4, showing the position of the parts when the indicator is held against depression;

Fig. 8 is a sectional view on line 8—8 of Fig. 3;

Fig. 9 is a section on line 9—9 of Fig. 4.

In the drawings I have shown my improvements applied to a lock having the usual mortise case 20 provided with a front plate 21, which may be covered by an ornamental face-plate 21a. In the lower part of the lock case is mounted a latch bolt 23. While the latch bolt mechanism per se forms no part of the present invention, it may be stated that this bolt is retractable from the inside by the usual knob spindle acting on a hub 24 to draw back a retracting shoe on yoke 25, and in the particular case illustrated, the outside knob which is connected by its spindle to a hub member 26 is permanently dogged against movement by a portion 26a on the hub member extending between the lugs 27 on the case. The knob shoe 25 has a shoulder 25a disposed in front of the cross-head 28 on the rear end of the latch bolt stem 29, which stem is surrounded by the usual spring 30 reacting against the guide lugs 30a of the case to normally urge the bolt 23 to protracted position. 95

In the upper part of the case a cylinder lock 31 is screwed in at the outer side and this lock through keys to be hereinafter described is adapted to actuate a latch retracting member 32 pivoted in the upper part of the case at 33 and having its lower extremity 34 disposed in front of the cross-head 28.

In the form of my invention shown, the usual dead-bolt has been omitted, and instead there is provided a flat slide member or blind bolt 35 provided with talons 36 adjacent the lock 31 and a cut away portion 37 between these talons at the forward end of the slide. As shown more particularly in 110

Figs. 8 and 9, the talons are offset laterally with reference to the body portion of the slide so that, as will be described hereinafter, one of the roll-backs of the lock 31 may operate above the body portion of the slide behind these talons, while the other roll-back is disposed in the plane of the talons. A fence or stump 38 formed rigidly with the lock case is received in a cut away portion 10 of the slide between these talons and the forward edge. This fence guides the slide in its reciprocating movement in the lock, and it is also guided in a similar manner at its lower side by one of the lugs 30^a. Below 15 the talons the slide has a cut away portion 39 to receive a thumb-turn hub 40, which is journaled in the case in a suitable manner. In the lower part of the cut-out or aperture 39 a gate 41 is formed to cooperate with a 20 wing 42 on the thumb-turn hub.

The slide is provided with a tumbler 43 pivoted on a post 44 at the forward part of the slide so as to be carried by the latter, and this tumbler is formed with a projection 45 25 extending between the talons 36 in a position to co-operate with a roll-back of the cylinder lock 31. This tumbler 43 is provided intermediate its ends with a lug 46 to co-operate with the post 38 in locking the 30 slide either in its retracted or advanced position. Below the tumbler 43 and pivoted to the lock case at 47 is a second tumbler 48 which co-operates with the thumb-turn hub when the latter is actuated to move the dead-locking mechanism. This tumbler is provided with a spring 49 reacting against a 35 post 50 rigidly formed with the lock case. The main part of the tumbler 48 overlies the body of the slide 35, and at its free end the 40 tumbler is provided with notches 51 and 52 which converge toward the upper edge of the tumbler. The spring 49 exerts an upward thrust upon the tumbler so as to keep it firmly seated against the thumb-turn hub 45 with the wing 42 engaged in one or the other of the notches 51 and 52. The tumbler in this manner exerts such an upward thrust on the wing 42 as to hold it, in co-operation with the edge of the gate 41, in 50 such a manner that the slide will be locked in either its retracted or protracted position and cannot be moved out of such position, except by the actuation of the thumb-turn hub or the lock 31 by means of the proper 55 key.

The two tumblers are joined by means of a connector 53 which may take the form of a small plate, as shown in the drawings. This plate is provided with upper and lower 60 pins 54 and 55 projecting rearwardly therefrom, the pin 54 being received in a slot 56 in the upper tumbler 43, and the lower pin 55 being secured in the lower tumbler. It will be apparent that the slotted connection 65 between the connector-plate 53 and the tum-

bler 43 is necessary due to the fact that relative movement of the tumblers must be permitted as one is mounted upon and moves with the slide, while the other is pivotally carried by a post rigid with the lock case. 70 In the construction shown, the slide 35 may be shifted together with the tumbler 43 without disturbing the connection with the upper movable tumbler with the lower tumbler mounted upon the fixed post. The upper part of the connector-plate is preferably notched or bifurcated, as shown at 57, to receive between its forks the post 38. The post thus guides the plate properly in its vertical movements when the tumblers are 80 depressed preparatory to shifting the dead-locking slide 35.

The slide 35 is provided at its lower side with a finger 35^a disposed rearwardly of the cross-head 28 upon the end of the latch bolt stem 29. As shown in Fig. 4 when the slide 35 is moved forwardly to its dead-locking or operative position this finger is moved to a position to engage behind this cross-head to prevent retraction of the latch bolt. 90

The cylinder lock 31, preferably of the kind shown in the patent to H. G. Voight, No. 1,243,016, granted October 16, 1917, is provided with the usual case 58 and key plug 59, the latter being controlled by the usual pin tumblers (not shown) cooperating with the key plug in the manner described in the patent referred to, and a pair of roll-backs 62 and 63, the former being rotated alone by all of the keys to the lock, except the emergency key which rotates both roll-backs. These roll-backs are spaced apart by parallel planes by means of a washer 64, and it will be apparent that while the operating projection 45 on the upper tumbler 43 is disposed in the plane of the roll-back 63 it is without the plane of the roll-back 62, the latter turning idly behind this projection, and thus not being capable of advancing or retracting the slide 35. 100

The latch-retracting lever 32, previously described, may be actuated from the cylinder lock by means of a lever 65 pivoted on the slide 35 at 67 and carried by the slide in its movement to and fro within the lock case. The free end 66 of this lever bears upon the upper edge of the lever 32 when the slide is in retracted position, so that by depressing the lever 65 the lever 32 may be actuated to retract the latch. For this purpose the lever 65 is provided adjacent the cylinder lock with a comparatively deep operating projection 68 close to and having portions in substantial alignment with both roll-backs 62 and 63, so that this lever may be operated by either of the roll-backs. It will be observed, however, that when the slide is in advanced position, as shown in Fig. 4, the lever 65 is not only out of contact with the latch-retracting lever 32, but it is also with- 110 115 120 125 130

out the range of movement of the roll-backs the lock case is a stop member 88 generally cylindrical in shape, and provided with a shoulder or flange 89 at its rear end to contact with the lock case and limit the outward movement of the stop member under the tension of a compression spring 90 mounted within a cavity within this member and re-acting at its rear end upon an L-shaped arm 91 secured to the front plate of the lock case. If, when the parts are in this position, the lock is operated by any key but the emergency key, the roll-back 62 rotates freely within a cavity within the lock case and re-acting at its rear end upon an L-shaped arm 91 secured to the front plate of the lock case. It will be obvious that under the tension of the compression spring 90 the stop member will be held in a position shown in Fig. 5, where it is this time held in a cavity within the lock case and will serve through the roll-back 63, substantially flush with the face-plate 21, first to move the slide 35 rearwardly to the rear of the lock. Pressure upon the push button 78, however, will cause the shank 82 of the lever 68 to be engaged by the plunger 90 to retract the stop member either roll-backs, and a continued rotation of the lock by the emergency key, or the rotation of the roll-back 62 by any of the keys, will serve to retract the latch through the push button whether or not the door has been locked.

In order to dog the knob when the latch bolt is dead-locked, I have shown a lever 71 pivoted upon the post 50 and engaged at its upper end with the slide 35, so that as the slide is moved forwardly the lower end of this lever will be moved downwardly and rearwardly behind a projection on the shoe 29 upon the stop member when the slide 35 is moved forwardly to dead-lock the latch 25 to prevent movement of the latter.

In order to indicate to a person without the room whether or not the door has been locked from the inside, or has been locked with a proper key (in this case the emergency key) from the outside, I have provided upon the door jamb an indicating mechanism similar to that shown in my co-pending application, Serial No. 574,396, filed July 12, 1922, of which this application is a continuation-in-part. Pivoted at 75 to the rear face of the strike-plate 76 is a lever 77, one end of which co-operates with a push button 78 mounted in an extension 79 in the strike-plate, the other end of this lever co-operating with the head 80 of a spring-

pressed indicator controller plunger mounted in a cylinder 81 in the strike-plate and provided with a shank 82 which is adapted to be projected through an opening 83 in the face of the plate. A coil spring 84 is mounted within the cylinder 81 and reacts against the rear of the face of the strike-plate and against the head 80 of the plunger to normally hold the plunger in its retracted position within the strike-plate, and by means of the lever 77 to normally hold the push button 78 in its outer position as shown in Fig. 5. The push button is also mounted in a cylinder 85 in the strike-plate, and both this cylinder and the cylinder 81 are provided with side notches 86 and 87 to permit the ends of the lever 77 to follow the push button and plunger in their movements in the cylinders.

Mounted in and extending through openings in the front face and the face-plate of

As shown in Fig. 3, the front portion of the slide 35 is provided with a recess 93 to receive the end of the L-shaped arm 91, so that the edge 94 of the slide may pass below the edge 95 of the arm and engage against the shoulder of the slide and the push button will be effectively blocked against depression. Thus an indication will be given to any one trying the push button that the door has been dead-locked. The operation of my lock may be briefly described as follows: The parts of the lock normally stand in the position shown in Fig. 3, wherein the latch may be freely retracted either by the knob 94 upon the inside of the door acting upon the retracting shoe 25, or by any of the keys from the outside, as all of the keys rotate the roll-back 63 which engages the projection 68 upon the lever 65 which in turn engages the latch-retracting lever 32. If the guest wishes to lock the door from the inside, he uses the thumb-turn 95 which serves to move the dead-locking slide 35 forwardly to the position shown in Fig. 4, wherein the finger 35^a is disposed behind the cross-head upon the stem of the latch bolt. It will be noted also that with the parts in this position the lever 65 has been moved forwardly until it is no longer engaged by either of the roll-backs 63, and at the same time the indicator mechanism is set so that it is impossible to depress the push button 78. If it is attempted to open the door by any except the emergency key the roll-back 63 alone will be rotated, and will not disturb the mechanism in any way as it turns freely behind the offset talons 36 upon the slide and as the lever 65 is now without the range of movement of

either of the roll-backs. The emergency key, however, if used at this time, since it operates both of the roll-backs, will first cause the slide to be retracted by the roll-back 62 to the position shown in Fig. 3 wherein a continued rotation of the lock will cause the roll-backs to engage the projection 68 upon the lever 65 and through the latch-retracting lever 32 the latch will be retracted 10 and the door opened. The feature of so arranging the parts of the lock that when the door is locked the usual keys will merely rotate idly is a very important one, as keys are very often broken or twisted when their 15 movement is resisted. While I have shown and described an indicator for a lock, I do not claim the same herein but have filed a separate application therefor bearing Serial No. 163,726 and filed January 26, 1927.

20 While I have shown and described a preferred embodiment of my invention, it will be understood that it is not to be limited to the details shown but is capable of variation and modification within the spirit of 25 the invention as defined by the scope of the appended claims.

What I claim is:—

1. In a door lock, a case, a latch bolt therein, key actuated means to retract said bolt including a lever pivoted to the case, and means to dog said bolt in protracted position, said retracting means being moved to position to allow said key to rotate freely when said dogging means is operative.
- 35 2. In a door lock, a case, a latch bolt therein, key actuated means to retract said bolt including a lever pivoted to the case, a reciprocable slide to dog said bolt in protracted position, said slide being moved to position to allow said key to rotate freely when said dogging means is operative.
- 40 3. In a door lock, a case, a latch bolt therein, dogging means for the latch bolt, retracting means for the latch bolt including a lever pivoted to the case, a key operated mechanism connected to said retracting means to operate the same, and means for breaking said connection to allow said key to rotate idly when said dogging mechanism is moved to operative position.
- 45 4. In a door lock, a case, a latch bolt therein, a reciprocating slide to dog said bolt in protracted position, retracting means for the bolt including a lever pivoted to the case, key operated mechanism connected to said means to actuate the same, and means for breaking the connection between said key operated mechanism and said retracting means to allow the key to rotate idly when 50 said dogging slide is moved to operative position.
- 55 5. In a door lock, a case, a latch bolt, therein, dogging means for said latch bolt, retracting means for the bolt including a lever pivoted to the case, a key operated

mechanism, and connections between said key operated mechanism and said retracting means, including a part movable with said dogging means, whereby said connection is broken to allow the key to rotate idly when 70 the dogging means is operative.

6. In a door lock, a case, a latch bolt therein, dogging means for the latch bolt, retracting means for the bolt including a lever pivoted to the case, a key operated 75 mechanism connected to said retracting means to actuate the same, and means to move said dogging means to operative position and simultaneously break said connection between said key operated mechanism 80 and said retracting means to permit the said key to rotate idly.

7. In a door lock, a case, a latch bolt therein, a reciprocating slide to dog the bolt in protracted position, retracting means for the bolt including a lever pivoted to the case, a key operated mechanism, and connections between said key operated mechanism and said retracting means, including a member movable with said slide, whereby 90 said connection is broken when the slide is moved to its dogging position.

8. In a door lock, a case, a latch bolt therein, a reciprocating slide to dog the bolt in protracted position, retracting means for the bolt including a lever pivoted to the case, a key operated mechanism, and connections between said key operated mechanism and said retracting means, including a member 95 mounted on said slide, whereby said connection is broken when the slide is moved to its dogging position.

9. In a door lock, a case, a latch bolt therein, a reciprocating slide to dog the bolt in protracted position, retracting means for the bolt including a lever pivoted to the case, a key operated mechanism, and connections between said key operated mechanism and said retracting means, including a member 100 pivotally carried by said slide, whereby said connection is broken when the slide is moved to its dogging position.

10. In a door lock, a case, a latch bolt therein, retracting means for the bolt including a lever pivoted to the case, a key operated mechanism, a reciprocable slide to dog the bolt in protracted position, a member carried by said slide normally engaging said retracting means, and adapted to be engaged in turn by said key operated mechanism, said means to be movable out of the path of said key operated mechanism when said slide is moved to dogging position to permit the key to rotate idly.

11. A lock comprising a latch bolt, a dead-locking slide for said latch bolt, key operated means for retracting said bolt, including a member mounted on said slide, a key actuated tumbler mounted on said slide, a second tumbler controlling the position of 125 130

the slide and connected with said first tumbler, a thumb turn for actuating the second tumbler, said member being moved to inoperative position when said slide is actuated by either thumb turn or key.

12. In a door lock, a latch bolt, a dead-locking slide for said latch bolt, retracting means for the latch bolt, including a member mounted on said slide, key operated mechanism to actuate said member, a pair of tumblers controlling the position of said slide, one being adapted to be engaged by a key and the other by a thumb turn, means interconnecting said tumblers, said member being moved out of position to be engaged by said key operated mechanism when said slide is moved to dead-locking position by either thumb turn or key.

13. In a door lock, a case, a latch bolt therein, retracting means for the bolt including a lever pivoted to the case, dead-locking mechanism within the case, a key

operated mechanism, and connections between said key operated mechanism and said lever including a part movable with said dead-locking means whereby said connection is broken to allow the key to rotate idly when the dead-locking means is moved to operative position.

14. In a door lock, a case, a latch bolt 30 therein, a dead-locking slide within said case, retracting means for the latch bolt, including a lever pivoted to the case, key operated mechanism for operating the latch bolt and the dead-locking slide, and connections between said key operated mechanism and said lever including a part movable with the slide whereby said connection is broken to allow the key to rotate idly when the slide is in dead-locking position.

In witness whereof, I have hereunto set my hand this 17th day of April, 1924.

JOHN H. SHAW.
